FRANK MOSSBERG, OF ATTLEBORO, MASSACHUSETTS, ASSIGNOR TO MOSSBERG
PRESSED STEEL CORPORATION, OF ATTLEBORO, MASSACHUSETTS, A CORPO-
RATION OF MASSACHUSETTS.

BEAM HEAD.

Application filed December 5, 1919. Serial No. 342,630.

To all whom it may concern:

Be it known that I, FRANK Mossberg, a citizen of the United States, and resident of the city of Attleboro, in the county of Bristol and State of Massachusetts, have invented certain new and useful Improvement in Beam Heads, of which the following is a specification.

This invention relates to heads for warp-beams and the like; and has for its object to provide a flange on the head which is adapted to be adjusted to grip and bind the body of the beam and also to provide a clamp-block in the head to assist in gripping, binding and fastening the head in adjusted position on the beam.

With these and other objects in view, the invention consists of certain novel features of construction, as will be more fully described, and particularly pointed out in the appended claims.

In the accompanying drawings:

Figure 1—is an end elevation of my improved beam head, illustrating the clamp-flange as adjustably attached thereto.

Figure 2—is a sectional edge elevation of the head on line 2—2 of Figure 1; also showing the head as mounted on the body of the beam, which latter is shown in dotted lines.

Figure 3—is a perspective view of the L-shaped strip which is subsequently bent into ring shape to form the clamping flange.

Figure 4—is an end view of the head, illustrating the clamp-flange as made in one piece, the abutting ends of the flange being normally separated to permit of being drawn together to bind the head upon the body of the beam.

Figure 5—is an edge sectional view on line 5—5 of Figure 4.

Figure 6—is an enlarged detail illustrating one of the clamp-blocks carried by the flange.

I have herein shown and described the construction of a head-member which is adapted to be adjustably mounted on the body of a yarn-beam or similar article as it is found in practice desirable in beams of the character described to be able to adjust the head longitudinally on the body to control the operating length of the beam between the heads.

With reference to the drawings, 10 designates the body of the beam which is shown in dotted lines, and 11 is one of the head members which is shown as being mounted upon the beam and secured in position thereon by binding and clamping mechanism.

In carrying out this invention the head-member is preferably constructed of a main plate 12 cut or formed from sheet stock into disk shape. The outer edge of which is designed to be stiffened either by rolling the same over a wire core 13 as illustrated in Figures 1 and 2 or by turning or bending the same off at an angle to the plane of the plate as illustrated at 14 in Figures 4 and 5, or the periphery of this plate may be stiffened in any other suitable way. The body of the plate itself may be formed plain as illustrated in Figures 1 and 2 or this plate may be provided with stiffening radial ribs as illustrated at 15 in Figures 4 and 5.

The feature of my present invention however, is the construction of a clamp flange member 16 which is preferably formed of bendable or ductile stock, the same being first bent into the form of an L-shaped strip of the desired length and then bent into a ring having one face 17 adapted to be adjustably secured to the outer face of the disk by means of rivets 18 or other suitable means, the other face of the flange extending at a right angle to serve as a broad faced bearing to engage the beam. The abutting ends 19 of the ring-shaped binding flange is normally slightly separated and provided with oppositely-disposed bosses 20 drilled to receive the binding bolt 21. In order to permit this collar or clamp flange a contracting or expanding movement on its plate I have slotted its face 17 as at 23 at the point where the rivets 24 pass therethrough thereby permitting the clamp flange to be contracted to bind and grip the body surface of the beam.

In other instances instead of forming this clamping flange in one piece as illustrated in Figure 4, I form the same in halves, as illustrated in Figure 1, in which case I provide bosses 25 at each end of the opposing halves, binding bolts 26 being passed through these bosses for the purpose of drawing together the halves to bind the same upon the body surface of the beam.

When the flange is made in halves as herein illustrated I slot the openings 27 through which the rivets 25 are passed thereby permitting a sliding movement of the flange 5 upon the surface of the disk 12.

It is found in practice that as these heads are more particularly adapted for use upon beams having wooden bodies that in some cases the mere binding of the clamp flange 10 upon the surface of the beam is insufficient to hold the head from slipping on the beam when great pressure is brought to bear upon the same.

Therefore to insure this head against movement after having been set in the desired position on the beam I have provided a clamp-block 29 having a broad-engaging face 30 extending inwardly through a corresponding opening in the flange 22, this 20 clamp block being provided with a flange 31 through which binding bolts 32 pass from the inner side outwardly, whereby when it is desired to positively secure this head in position on the beam it is only necessary to 25 screw down the nuts 33 and so force the engaging surface of the clamp block 29 down onto the wooden surface of the beam thereby positively gripping and holding the head against movement on the beam under 30 the most severe conditions.

My improved beam-head is adapted to be constructed entirely of sheet metal; is very

strong and durable and efficient in its operation.

The foregoing description is directed 35 solely towards the construction illustrated, but I desire to be understood that I reserve the privilege of resorting to all the mechanical changes to which the device is susceptible, the invention being defined and limited 40 only by the terms of the appended claims.

I claim:

1. A beam-head comprising a metal disk, a clamp flange formed of two ring halves, each L-shaped in cross section and adjustably mounted on said disk, means for relatively adjusting said ring halves on said disk to bind the beam thereto, and clamp-block having a portion adjustably mounted on the outer face of said flange and adapted to be 45 forced inwardly to bite the body of the beam.

2. A beam-head comprising a metal disk, a clamp flange formed of a ring of sheet metal L-shaped in cross section and adjustably secured to said disk, means in said 55 clamp-ring for adjusting the working diameter, a clamp block extending through an opening in said ring, and provided with side flanges having adjustable means for forcing said block inwardly against the beam to grip 60 bind and fasten the head thereto.

In testimony whereof I affix my signature.

FRANK MOSSBERG.
